UNITED STATES PATENT OFFICE

HARRY LEE COWAN, OF LOS ANGELES, CALIFORNIA

DESIGN FOR A PROJECTING MACHINE

Application filed September 19, 1932. Serial No. 44,992. Term of patent 3½ years.

To all whom it may concern:

Be it known that I, HARRY LEE COWAN, a citizen of the United States, residing at Los Angeles, in the county of Los Angeles and State of California, have invented a new, original, and ornamental Design for Projecting Machines, of which the following is a specification, reference being had to the accompanying drawing, forming part thereof.

The figure is a perspective view of a projecting machine, showing my new design.

I claim:

The ornamental design for a projecting machine substantially as shown.

In testimony whereof, I hereunto affix my signature this 14th day of September, 1932.

HARRY LEE COWAN.
